CLAIM

The ornamental design for a display screen with animated graphical user interface, as shown and described.

DESCRIPTION

FIG. 1 is a front view of the first image in the sequence for a display screen with animated graphical user interface showing our new design;

FIG. 2 is a front view of the second image thereof;

FIG. 3 is a front view of the third image thereof;

FIG. 4 is a front view of the fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof;

FIG. 9 is a front view of a ninth image thereof;

FIG. 10 is a front view of the tenth image thereof.

FIG. 11 is a front view of the eleventh image thereof; and, FIG. 12 is a front view of the twelfth image thereof.

The broken lines illustrate an electronic device and form no part of the claimed design. The outermost solid-line rectangle illustrates the perimeter of a display screen. The appearance of the animated graphical user interface sequentially transitions between the images shown in FIGS. 1–12. The process or period in which one image transitions to another image forms no part of the claimed design.
